REFRIGERATOR CAR DOOR

William M. Dwyer, Chicago, Ill., assignor to W. H. Miner, Inc., Chicago, Ill., a corporation of Delaware

Application October 19, 1936, Serial No. 106,300

15 Claims. (Cl. 20—23)

This invention relates to improvements in refrigerator car doors.

One object of the invention is to provide a door construction for refrigerator cars comprising a sliding door member for closing the door opening of the car, and means for supporting the door for movement toward and away from the side of the car, wherein simple and efficient manually actuated means is employed for moving the door into the door opening and forcing the door tightly closed or prying the door open and moving the same out of the door opening, so designed that the supporting means is entirely relieved from strain during the final closing and initial opening operations while the door is being forced tightly closed and pried open.

A further object of the invention is to provide means of the character described in the preceding paragraph, which is so designed and arranged that the projection of the parts thereof will not exceed certain predescribed limits so that the mechanism will clear the usual loading platform structure, tunnel walls, and all other obstructions encountered in standard railway practice.

Another object of the invention is to provide in a door construction of the character hereinbefore described, efficient, manually actuated mechanism for successively moving the door into the door opening and forcing the same to tightly closed position or successively prying the door open and moving the same to a position clear of the car wall, comprising crank arms for supporting and moving the door into and out of the door opening, and keeper and cooperating keeper engaging means for effecting the final closing and initial opening movements of the door, wherein the keeper means is mounted on the car wall and the cooperating keeper engaging means is actuated independently of the supporting crank arms during said final closing and initial opening movements of the door, thereby assuring tight closing and forcible opening movements of the door without subjecting the supporting means to any excessive strains during these operations.

A more specific object of the invention is to provide a door construction and operating means therefor of the character described in the preceding paragraph, so arranged and designed that the manually actuated means which effects opening and closing movements of the door controls the operations of the crank arms and the keeper engaging means to effect movement of the door rapidly inwardly and outwardly through positive actuation of the crank arms and to bring the keeper engaging means into and out of coopera-

tive relation with the keepers and effect operation of the keeper engaging means in the final closing and initial opening movements of the door, with slower movement of said arms in synchronism with the movement produced by said keeper engaging means.

A still further object of the invention is to provide in a sliding door construction for refrigerator cars, actuating means engageable with rugged and substantial fixed keepers for either forcing the door tightly closed after it has been moved to partly closed position, or prying the same partly open, the actuating means being designed to operatively connect with movable supporting means for the door to actuate the supporting means to either move the door into the door opening to said partly closed position, or withdraw the door from said door opening.

Yet another object of the invention is to provide an operating means of the character set forth in the preceding paragraph, which, during the final closing and initial opening movements of the door, is automatically disconnected from the movable means for supporting and guiding the door.

Other objects of the invention will more clearly appear from the description and claims hereinafter following.

In the drawings forming a part of this specification, Figure 1 is an elevational view, partly broken away, of the side wall of a refrigerator car, illustrating my improvements in connection therewith, said view showing the door closed. Figure 2 is a view corresponding to Figure 1, on an enlarged scale, of the mechanism shown at the lower left hand corner of Figure 1. Figure 3 is a horizontal sectional view, corresponding substantially to the line 3—3 of Figure 2. Figure 4 is a view, similar to Figure 3, but showing the parts in position with the door withdrawn from the door opening clear of the side wall of the car. Figure 5 is a broken, vertical, sectional view, on an enlarged scale, corresponding substantially to the line 5—5 of Figure 1. Figure 6 is a view, similar to Figure 5, but showing the door withdrawn from the door opening to clear the side wall of the car. Figure 7 is a view, similar to Figure 1, illustrating another embodiment of the invention. Figure 8 is a view corresponding to Figure 7, on an enlarged scale, of the mechanism shown at the lower left hand corner of Figure 7. Figure 9 is a horizontal sectional view, corresponding substantially to the line 9—9 of Figure 8. Figure 10 is a view, similar to Figure 5

9, but showing the door withdrawn from the door opening to clear the side wall of the car.

In said drawings, 20 indicates the side wall of the car, which side wall is provided with the 5 usual door opening 21 closed by a single door 22. The door 22 is slideable lengthwise of the car and is displaceable laterally in reverse directions to either move the door into or withdraw it from the door opening 21. As shown, the cooperating 10 engaging edge faces of the door and walls of the door opening are beveled and the usual insulating packing material indicated at 23 is employed to seal the joint between the door and walls of the door opening.

15 Referring first to the embodiment of the invention illustrated in Figures 1 to 6 inclusive, my improvements comprise broadly top and bottom tracks A—A; carriers B—B cooperating with the bottom track A; pairs of top and bottom supporting brackets C—C and C—C; a pair of vertically disposed, combined, operating and keeper engaging crank shafts D—D; pairs of top and bottom keepers E—E and E—E; pairs of top and bottom supporting crank shafts F—F and F—F; 20 pairs of sliding rack members G—G and G—G; interrupted pinion gears H—H and H—H on the combined operating and keeper engaging crank shafts D—D meshing with the rack members G—G and G—G; and interrupted pinion gears 25 K—K and K—K on the supporting crank shafts F—F and F—F cooperating with the rack members G—G and G—G.

The top and bottom tracks A—A, which are disposed respectively above and below the door opening 21, are of such a length that the door 22 may be slid entirely clear of the door opening. The bottom track A is in the form of an elongated bar having a substantially flat, vertically disposed, section 24 fixed to the side wall 30 of the car, a horizontally disposed outstanding section 25 at the bottom of the section 24, and a vertically disposed flange section 26 at the outer edge of the section 25, the flange section 26 forming the rail member proper of the track. The 40 top track A comprises an elongated, flat, barlike section 27 secured to the side wall of the car and an elongated bar member 28 of substantially Z-shaped cross section fixed to the section 27, with the lower flange of the former spaced outwardly from the section 27 to provide a downwardly facing guide channel 29 therebetween. As most clearly shown in Figure 1, each track A is provided with a stop member 30 at the left hand end thereof, said stop member being preferably in the form of a block fixed to the track in any suitable manner. The stop block 30 of the bottom track A is preferably secured to the vertical section 24 of said track and extends into the channel between said section and the flange 45 26. The stop block 30 of the top track is seated in the channel 29 thereof and is fixed to the side walls of said track.

The combined operating and keeper engaging shafts D—D are arranged vertically and disposed at opposite sides of the door, each shaft D being rotatably supported by the corresponding top and bottom brackets C—C, which brackets are secured to the door adjacent to the top and bottom edges thereof. Each shaft D is provided with an operating handle lever 31, which is pivoted to the shaft for swinging movement in a vertical plane, so that it may occupy either the horizontal position shown in Figure 1 or may be dropped to a vertical position parallel to said shaft. At the 55 top and bottom ends, each shaft D is provided

with end members 32—32 which are fixed to said shaft and have crank arms 33—33 at the outer ends thereof extending radially therefrom and provided with keeper engaging pin portions 34—34 at their outer ends. The keeper engaging portions 34—34 are of generally cylindrical form and each has a flattened face portion 35 for a purpose hereinafter described.

The supporting brackets C—C and C—C are of similar design, the top brackets being arranged reversely to the bottom brackets. These brackets are preferably in the form of castings secured to the outer side of the door, each casting having a pair of vertically disposed, partly cylindrical bearing sleeves 36—36 formed integral therewith. The bearing sleeves 36—36 of each bracket are laterally spaced as shown most clearly in Figures 1, 2, 3, and 4, and extend outwardly from the main body portion of the casting to the edge of the door. The sleeves 36—36 are enlarged in diameter at their inner ends, as indicated at 37—37, and these enlarged sections open into a horizontally arranged housing portion 38 of said casting. The housing portion 38 has a horizontally extending, interior guideway 138 on the inner side thereof adapted to slidably accommodate and guide the corresponding rack member G.

The top and bottom end members 32—32 of each shaft D are provided with cylindrical bearing sections inwardly of the crank end portions thereof, which bearing sections are journaled in the innermost sleeves 36—36 of the corresponding top and bottom brackets C—C. The parts are so proportioned that the top and bottom keeper engaging crank members of each shaft D project a sufficient distance beyond the top and bottom edges of the door to properly cooperate with the corresponding pair of keepers E—E. Each shaft D is provided with two gear members H—H, these gear members being preferably formed integral with the end members 32—32. The gear member H of each end member 32 is disposed at the inner end of the cylindrical bearing section thereof and occupies the enlarged portion 37 of the innermost bearing sleeve 36 of the cooperating supporting casting C. As shown most clearly in Figures 3 and 4, each of the gears H has the teeth thereof interrupted, thereby providing part gear members for a purpose herein-after pointed out. Each end member 32 also has a short cylindrical bearing section beyond the corresponding gear H, said bearing section being journaled in a bearing member 39 of the housing portion 38 of the bracket C.

The supporting crank shafts F—F and F—F are arranged in pairs at opposite sides of the door, one member of each pair at the top and the other at the bottom of said door. Each crank shaft F comprises a vertically disposed, cylindrical shaft portion 40, a radially disposed arm 41 at the outer end of said shaft portion, a vertically disposed, cylindrical, bearing projection or pin 42 at the outer end of the arm 41, and a gear member K formed integral with the shaft portion 40 adjacent to the inner end of the latter. Each crank shaft F has the shaft portion 40 thereof journaled in the outer bearing sleeve 36 of the corresponding supporting casting C and has the gear K thereof accommodated in the enlarged section 37 of said sleeve. The teeth of the gear K of each shaft F are interrupted, as clearly shown in Figures 3 and 4, for a purpose herein-after pointed out.

The crank shafts F—F and F—F serve to 75

support and guide the door in its movements into and out of the door opening, and are slidingly guided by the top and bottom tracks A—A.

The carriers B—B which cooperate with the bottom track A support the bottom crank members F—F. Each carrier B is in the form of an elongated slide having enlarged end portions housing anti-friction supporting rollers 43—43 which are rotatably journaled in said slide and project therefrom to engage with said bottom track A. These anti-friction rollers are preferably grooved, as shown in Figures 5 and 6, to receive and ride on the upstanding flange 26 of said bottom track A. Substantially midway between the ends thereof, each carrier B is provided with a vertically disposed, cylindrical bearing opening 44 in which the bearing or pivot pin 42 of the corresponding bottom supporting crank shaft F is journaled. The bearing pin portions of the top crank shafts F—F extend into the channel 29 of the top track A and carry anti-friction rollers 45—45 which are journaled thereon for rotation about vertical axes and substantially fit between the side walls of said track to properly support and guide the top crank arms for sliding movement lengthwise of the car. As will be evident, the door 22 is thus supported for sliding movement lengthwise of the car and for movement into and out of the door opening by the top and bottom crank shafts F—F and F—F, the arms of which have pivotal swinging connection with the supporting and guiding carriers on said tracks, the rollers 45—45 forming carriers which cooperate with the top track A.

The rack members G—G and G—G are all of similar design. Each rack member G is in the form of an elongated bar of channel-shaped cross section guided in the horizontal guideway 138 of the corresponding supporting casting C. Each rack G is provided with two sets or series of rack teeth 46 and 47, said two sets of teeth being spaced apart as clearly shown in Figures 3 and 4, and the set 47 being of greater length than the set 46 and meshing with the teeth of the gear H of the corresponding end member of one of the shafts D. The two sets of teeth are so arranged that the set 46 is out of mesh with the gear K of the supporting crank shaft member F when the parts are in the position shown in Figures 1, 2, 3, and 5, and are brought into mesh with said gear when the rack is moved a sufficient distance to the right, as viewed in Figures 1, 2, and 3, to effect rotation of the crank shaft F.

The keepers E—E and E—E are preferably in the form of castings secured to the side wall of the car in pairs at opposite sides of the door opening, the members of each pair being in vertical alignment and disposed respectively above and below the door opening 21. Each keeper E is provided with an outwardly opening, inclined guideway which forms, in effect, a cam groove or way 48, adapted to accommodate the keeper engaging pin portion 34 of the crank arm 33 of the corresponding crank member of one of the shafts D. These keepers E—E and E—E are so positioned that, when the door 22 is moved in front of the opening 21 and the crank arms F—F and F—F are rotated to swing the door inwardly, the keeper engaging portions 34—34 and 34—34 of the shafts D—D will be aligned with and enter into the slots or cam ways 48—48—48—48 of the keepers.

Latch means 49—49 of any well-known type is employed to lock the operating handles 31—31 of the shafts D—D in the position with the door

closed, as illustrated in Figure 1. Additional latch means 50—50 of any well-known design is also provided for locking the operating levers 31—31 in position when the same have been swung through a straight angle from the position shown in Figure 1, in rotating the shaft to open the door. When thus locked by the latch members 50—50, the levers 31—31 of the shafts D—D hold the latter and the intergeared crank shafts F—F and F—F against rotation to hold the door in parallel relation to the side wall of the car and against lateral displacement while the same is being slid along the tracks A—A.

The operation of my improved mechanism shown in Figures 1 to 6 inclusive in opening the door is as follows: With the door closed, as shown in Figure 1, after unlocking the handle levers 31—31, each lever is swung outwardly away from the door, thereby rotating the corresponding shaft D. These handle levers may be actuated either simultaneously or successively, as desired. As will be evident, the shafts D—D will thus be rotated in opposite directions. Except for the fact that the shafts D—D are rotated in opposite directions, the operation thereof is the same in each instance. Upon rotation of either of the shafts D, the top and bottom gears H—H thereof which are in mesh with the top and bottom racks G—G will effect sliding movement of said racks, the racks G—G associated with the shaft D at the left hand side of the door being moved to the right, and the racks G—G associated with the shaft D at the right hand side of the door being moved to the left. During rotation of each shaft D, the keeper engaging crank members thereof, which are in operative engagement with the corresponding keepers E—E, will pry the door out of the door opening. During this movement of the shafts, the keeper engaging crank members will leave the cam ways of the keepers E—E and the toothed rack sections 46—46 of the racks G—G will be brought into mesh with the interrupted pinion gears K—K of the crank members F—F and rotate the latter to swing the door outwardly to the position shown in Figure 4. When the parts are in the position shown in Figure 4, the shaft D will have been rotated through an arc of approximately 180° and the operating handle lever 31 thereof will be disposed at the side of the shaft opposite to that occupied in Figure 1. The attendant then locks the lever 31 to the door by means of the latch 50, thereby holding the shaft D against rotation and through the geared connection with the crank shafts F—F, also locking the latter in fixed position. As will be evident, when both shafts D—D have been thus operated and locked in position, the door will be held spaced from the side wall of the car a sufficient distance to clear said wall, as clearly disclosed in Figures 4 and 6. The attendant then slides the door along the tracks to completely clear the door opening. In closing the door 22, the same is slid to the position in front of the door opening 21, as shown in Figure 4. The actuating levers 31—31 are then unlocked and the shafts D—D rotated in reverse directions to the directions hereinbefore described, thereby sliding the racks G—G and G—G and rotating the supporting crank members F—F and F—F to swing the door 22 into the door opening. During this rotation of the shafts D—D and the crank members F—F and F—F, the keeper engaging crank ends of the shafts D—D will be brought into alignment with the cam ways of the keepers E—E and E—E. As the keeper engaging or crank

pin portions 34-34 of the crank arms of each shaft D enter the cam ways of the keepers, the teeth 46-46 of the racks G-G will clear the gears K-K, thereby permitting free rotation of the crank members 31-31 during the remainder of the door closing operation.

Continued rotation of the shafts D-D will bring the crank pins 34-34 into engagement with the outer walls of the cam ways of the keepers E-E and cam the door inwardly to the position shown in Figures 1 and 3. The operating handle levers 31-31 of the shafts D-D are then locked in position by the latch members 49-49, as shown in Figure 1. The gears H-H and H-H of the shafts D-D are at all times in mesh with the racks G-G and G-G, and as the rotation of these shafts is through an arc not greater than 180°, only partial sets of teeth are required on these gears, but, as will be evident, the teeth 20 need not be interrupted and gears having complete sets of teeth around their circumference may be employed without effecting or altering the operation of the mechanism.

When the door is closed, the flat faces 35-35 and 35-35 of the crank pins 34-34 and 34-34 are in flat bearing engagement with the outer walls of the slots of the keepers K-K and K-K, as clearly shown in Figure 3, thereby locking the shafts D-D against accidental rotation.

Referring next to the embodiment of the invention illustrated in Figures 7, 8, 9, and 10, the construction is substantially the same as that illustrated in Figures 1 to 6, with the exception that the racks G-G and G-G are omitted and the gears on the combined operating and keeper engaging shafts D-D are adapted to mesh directly with the gears on the supporting crank shafts F-F and F-F, and that the supporting brackets for the shafts D-D and the crank shafts F-F and F-F, which correspond to the brackets C-C and C-C, are modified accordingly. These supporting brackets are indicated by M-M and M-M in Figures 7, 8, 9, and 10.

As shown in the last named figures, the end members 32-32 of each shaft D are provided with integral enlargements forming gear members P-P which have interrupted teeth 51-51, and the cooperating supporting shafts F-F are provided with integral enlargements forming gears R-R which have interrupted teeth 52-52. The bearing portions of each shaft D are rotatably supported in outer bearing sleeve sections 53-53 formed on the corresponding top and bottom supporting brackets M-M, and the bearing portions of the cooperating crank shafts F-F are journaled in the inner bearing sleeve sections 54-54 of said brackets. Each bearing bracket M is provided with a suitable housing portion 55 for the gears P and R.

As shown most clearly in Figures 9 and 10, the first tooth at the right hand end of the set of teeth 51 of the gear P is shortened so that it will clear the second tooth from the left hand end of the set of teeth 52 of the gear R, whereby engagement of said end tooth of the gear P with the end tooth of the set of teeth 52 of the gear R is assured.

In the operation of the mechanism shown in Figures 7 to 10 inclusive, assuming that the door 22 is in the closed position shown in Figures 7, 8, and 9, rotation of the shaft D in a clockwise direction, as viewed in Figure 9, effects outward camming of the door through operation of the keeper engaging crank ends of the shaft D, which 75 crank ends are in engagement with the keepers

E-E. The door is thus forced open in the same manner as the construction illustrated in Figures 1 to 6 inclusive. As the door is pried outwardly the keeper engaging crank ends of the shaft D will pass out of the cam slots of the keepers E-E and at the same time the teeth 51-51 of the gears P-P will be brought into mesh with the teeth 52-52 of the gears R-R and upon further continued rotation of the shaft D, the crank shafts F-F will be rotated to swing the arms thereof outwardly and completely withdraw the door 22 from the door opening 21, as shown in Figure 10.

In closing the door, each shaft D is rotated in a reverse direction to swing the crank shafts F-F inwardly to move the door into the door opening and then cam the door to tightly closed position by means of the keeper engaging crank members of the shafts D-D, in the same manner as described in connection with the construction shown in Figures 1 to 6 inclusive. As will be evident, in the closing operation the gear teeth 51 of the gears P will become completely disengaged from the teeth 52 of the gear R when the keeper engaging crank ends of the shaft D enter the cam slots of the keepers E-E, thus leaving the crank shafts F-F free to rotate as the arms thereof are swung through inward movement of the door by the action of the keeper engaging crank members.

I have herein shown and described what I now consider the preferred manner of carrying out my invention, but the same is merely illustrative and I contemplate all changes and modifications that come within the scope of the claims appended hereto.

I claim:

1. In a door construction for refrigerator cars having a wall member provided with a door opening, the combination with a door adapted to close said opening; of guide track means on said car; carrier means slidably guided on said guide track means; and means for moving said door to open or close the same, including a manually actuated operating member movably mounted on the door, fixed keeper means with respect to which the carrier means is movable, movable means supporting the door on said carrier means, means for actuating said movable means by operation of said member to move said door either into or out of the door opening, and means on said operating member engageable with said keeper means for either prying the door open or forcing the same tightly closed.

2. In a door construction for refrigerator cars having a wall member provided with a door opening, the combination with a door adapted to close said opening; of guide track means on said car; carrier means slidably guided on said track means; and means for moving said door to open or close the same including a manually actuated operating member movably mounted on said door, fixed keeper means with respect to which said carrier means is movable, keeper engaging means on said operating member engageable with said keeper means for either forcing said door tightly closed or prying the same partly open, movable means supporting the door on said carrier means for movement toward and away from the door opening, means for transmitting motion from said operating member to said movable means for actuating the latter to move said door either into the door opening to engage said keeper engaging means with the fixed keeper means or out of the door opening 75

to disengage said keeper engaging means from said fixed keeper means.

3. In a door construction for refrigerator cars having a wall member provided with a door opening, the combination with a door adapted to close said opening; of guide track means on said car; carrier means slidably guided on said guide track means; and means for moving said door to open and close the same including a manually actuated rotary operating bar mounted on the door, fixed keeper means on the car with respect to which said carrier means is movable, supporting arms rotatably mounted on the door and pivoted for swinging movement on said carrier means, keeper engaging means on said operating bar engageable with said keeper means for forcing the door either tightly closed or pryng the same partly open, and drive means connecting said operating bar and arms for rotating the latter to displace the door to either engage said keeper engaging means with the keepers or disengage the same therefrom.

4. In a door construction for refrigerator cars having a wall member provided with a door opening, the combination with a door adapted to close said opening; of guide track means on said wall member; carrier means slidably guided on each track; fixed keepers on the car wall; rotary supporting crank shafts mounted on the door, said shafts having the outer ends of the crank arms thereof pivotally supported on said carrier means; a manually actuated rotary operating bar mounted on the door; keeper engaging means on said bar engageable with said keepers; and interrupted gear means operatively connecting said operating bar and crank shafts to rotate the latter during part of the door opening and closing operations.

5. In a door construction for refrigerator cars having a wall member provided with a door opening, the combination with a door adapted to close said opening; of guide track means on said wall; carrier means slidably guided on said track means; fixed keeper means on the car wall; swinging arms pivotally supported at their outer ends on said carrier means and swingingly supported at their inner ends on the door for guiding said door either into or out of the door opening; a manually actuated rotary operating shaft on the door, said shaft having keeper engaging means engageable with said keepers; and gear means connecting said arms and operating shaft for swinging said arms, said gear means including driving and driven members, one of said members having interrupted teeth to effect disconnection of said gears during part of the opening and closing movements of said door.

6. In a door construction for refrigerator cars having a wall member provided with a door opening, the combination with a door adapted to close said opening; of guide track means on said wall member; carrier means slidably guided on said track means; fixed keeper means on the car; a supporting crank member rotatably mounted on the door and having the outer end of the crank arm thereof journaled on said carrier means; a manually actuated rotary operating bar mounted on the door, said bar having keeper engaging crank means adapted to engage with said keeper means; and means for rotating said crank arm including a sliding rack member, and cooperating gears on said crank arm and operating bar, said rack having the teeth thereof interrupted to effect disengagement of said rack from the gear of

the crank arm during part of the rotation of said operating bar.

7. In a door construction for refrigerator cars having a wall member provided with a door opening, the combination with a door adapted to close said opening; of guide track means on said wall member; carrier means slidably guided on said track means; fixed keeper means on the car; a supporting arm rotatably journaled at one end on the door and at the other end on said carrier means; an operating shaft rotatably mounted on the door, said shaft having keeper engaging means rotatable therewith and engageable with said keeper means; and intermittent driving gear connections between said shaft and arm for intermittently effecting rotation of the latter during rotation of said shaft.

8. In a door construction for refrigerator cars having a wall member provided with a door opening, the combination with a door adapted to close said opening; of guide track means on said wall member; carrier means slidably guided on said track means; fixed keepers on said wall; supporting crank arms rotatably mounted on said door and pivotally supporting the door on said carrier means; a rotary operating shaft mounted on said door, said shaft having keeper engaging crank members cooperating with said keepers; and means driven by said operating shaft for rotating said arms with respect to the door while said keeper engaging crank members are disengaged from said keeper means, including intermeshing gear means having the toothed portions thereof interrupted to effect disengagement of said gear means during operative engagement between said keeper engaging crank means and keeper means.

9. In a door construction for refrigerator cars having a wall member provided with a door opening, the combination with a door adapted to close said opening; of guide track means on said wall member; carrier means slidably guided on said track means; fixed keepers on said wall; supporting crank members journaled on the door and having the outer ends of the crank arms thereof journaled on the carrier means; a rotary operating shaft on said door having keeper engaging means thereon engageable with said keepers; and cooperating interengageable rotary gears fixed to said operating shaft and crank members for driving the latter, said gears having the teeth thereof interrupted to effect disengagement thereof during part of the rotation of said shaft.

10. In a door construction for refrigerator cars having a wall member provided with a door opening, the combination with a door adapted to close said opening; of guide track means on said car; carrier means slidably guided on said track means; keeper means fixed to said car wall; a rotary operating bar on said door having means thereon engageable with said keepers; rotary supporting shafts on said door journaled on axes eccentric to said operating bar; radial supporting arms on said shafts pivotally supported at their outer ends on said carrier means; and intermittent drive means operatively connecting said operating bar to said shafts for rotating the latter during rotation of said operating bar.

11. In a door construction for refrigerator cars having a wall member provided with a door opening, the combination with a door adapted to close said opening; of guide tracks on said car; swinging supporting arms slidably guided at their outer ends on said tracks and rotatably connected at their inner ends to the door; gear

- means for rotating said arms on said door; a rotary operating shaft on said door; driving gears fixed to said shaft; sliding racks on said door reciprocated by said gears, said racks having interrupted toothed engagement with said gear means for intermittently driving the latter to impart rotary movement to said arms; keepers on said car wall; and keeper engaging means on said shaft rotatable therewith and engageable with 5 said keepers to force said door either tightly closed or pry the same open.
12. In a door construction for refrigerator cars having a wall member provided with a door opening, the combination with a door adapted 15 to close said opening; of guide tracks on said car wall; supporting crank shafts journaled on said door and having the outer ends thereof swingingly supported from said tracks; gears on said crank shafts, each of said gears having an 20 interrupted set of gear teeth thereon; keeper means on the car wall; a rotary operating bar journaled on said door; gears on said bar meshing with said interrupted sets of teeth of said first named gears; and keeper engaging crank 25 members on said rotary shaft engageable with said keeper means.
13. In a door construction for refrigerator cars having a wall member provided with a door opening, the combination with a door adapted to 30 close said opening; of guide tracks on said car wall; a supporting crank shaft journaled on said door and having swinging connection with said tracks; a gear on said crank shaft; a keeper on the car wall; a rotary keeper engaging member on said door engageable with the keeper for 35 forcing the door tightly closed or prying the same partly open; a gear fixed to said rotary keeper engaging member; and a reciprocating rack bar on said door cooperating with the gears of said 40 crank shaft and keeper engaging member, the teeth of said rack being interrupted to permit disengagement of said rack from the gear of said crank shaft.
14. In a door construction for refrigerator cars, having a wall member provided with a door opening, the combination with a door adapted to close said opening; of guide tracks on said wall member; supporting crank shafts journaled on said door and having swinging connection with said tracks; keepers on the car wall; rotary keeper engaging crank members mounted on the door; and means for rotating said keeper engaging crank members and shafts including reciprocating rack means operatively connected to gears on said keeper engaging crank members and crank shafts.
15. In a door construction for refrigerator cars having a wall member provided with a door opening, the combination with a door adapted to close said opening; of guide tracks on said 2 wall member; supporting crank shafts journaled on said door and having swinging connection with said tracks; keepers on the car wall; rotary keeper engaging crank members mounted on the door; and means for rotating said keeper 2 engaging crank members and crank shafts including driving connections between said keeper engaging crank members and crank shafts for producing synchronized rotary movement thereof to swing said crank shafts on said tracks to 30 displace said door either inwardly or outwardly with respect to the side of the car and either bring said keeper engaging members into operative engagement with the keepers or remove the same from said operative engagement and rotate said keeper engaging members while engaged with the keepers to either force said door tightly closed or pry the same partly open.

WILLIAM M. DWYER. 40
